CONTINUOUS FEED CUPOLA

Walter K. Hesse, Martinsville, N.J., assignor to Johns-Manville Corporation, New York, N.Y., a corporation of New York

Filed May 31, 1961, Ser. No. 113,696
3 Claims. (Cl. 214—18.2)

This invention relates to a continuous feed mechanism for cupolas of the type used for melting the materials, such as rock, glass and slag to be converted into fiber using a combustion agent such as coke or other carbonaceous material.

In this type cupola, as particularly used over the past many years in the production of mineral wool, it has been customary to provide batch feeding of slag and coke into the cupola with only moderate and sporadic attempts to place these materials in their most favorable positions in the cupola. The result has been that unnecessary variations in the feed rates, the slag-coke ratio and in the conditions of the issuing molten slag stream have been accepted as unavoidable.

In accordance with the present invention it has been found possible to introduce slag or rock mixtures and coke into typical upright mineral wool cupolas, fed from above as is customary, and to feed these materials on a continuous basis with only small and inconsequential variations in the feed rate or in the positioning of the materials in the cupola.

Tests have shown that by use of the present invention the materials can be uniformly placed in the cupola hour after hour in the most desirable conditions required for economy of operation, producing a slag stream of substantially uniform volume, temperature, and viscosity definitely superior to those heretofore produced for fiberization into light weight mineral wool products.

It is thus a primary object of the invention to provide a new and improved feeding mechanism for introducing the charge for the cupola, comprising the material to be melted and the required amount of combustion agent, at a substantially uniform rate, with the charge introduced into the upper portion of the cupola, over the burden previously placed in the cupola.

It is a further object to provide a feeding apparatus of this type in which the fines and coarser particles are suitably placed in the cupola for maximum economy and efficiency and in which the rate of feed varies only slightly and for short periods of time from the normal feeding rate established for the particular cupola and charge being utilized.

The above and other objects will be clear from the following description when considered in connection with the drawings wherein:

FIG. 1 is a vertical sectional view of the cupola and feed mechanism, parts being in elevation;

FIG. 2 is a horizontal sectional view thereof, taken on the line 2—2 of FIG. 1, parts being in elevation;

FIG. 3 is an elevational view of the cupola and feed mechanism, taken on the line 3—3 of FIG. 1, parts being broken away;

FIG. 4 is a diagrammatic view illustrating the relation of the various control and operating elements of the equipment.

Referring to the details of the drawings the cupola 2 is of any preferred design of upright cupola, that shown having a water jacketed cylindrical body, preferably of 3 to 5 feet in diameter. The lower portion, where the molten material is withdrawn and formed into mineral wool fibers is omitted, as it is a standard construction.

The devices for providing a continuous supply of slag and coke include two or more hoppers or bins 4, each containing a substantial quantity of materials, one pref-

2

erably containing coke and the other a mixture of materials to be melted. It is possible to pre-mix the coke with the materials to be melted and to use one bin for the supply. It is also possible to provide several bins for the coke and for each of the materials to be melted. However it has been found that best results are obtained by supplying one bin for coke and another for the pre-mixed materials to be melted.

The charge of materials to be melted for forming mineral wool varies considerably, depending on what materials are readily available, the type product desired, etc. Formulae for this purpose are well known, mixtures composed mainly of iron slag with minor proportions of modifying mineral materials, including some fines of these materials, being customarily used. The charge is referred to herein as "slag" charge, it being understood that by this term is meant any meltable slag or stone-like material or mixture available for the production of mineral wool.

The hoppers or bins 4, preferably of reduced width at their lower ends as shown at 5, may be provided with any type of removal equipment which can be operated on a continuous basis and which will discharge a uniform quantity of the stored materials. There is illustrated a preferred mechanism for this purpose, comprising reciprocating floor panels 6, supported on rollers 8 and movable back and forth under the stored materials. The panels 6 fit snugly against the bottom walls of the bins on the side and back walls thereof but the front wall is cut away as shown at 10. The floor panels extend outwardly beyond the front wall to provide a lip 12 on which the removed materials rest until the panel is withdrawn and the materials thereon are forced off of the panel by pressure of the materials in the bin. Adjustable hinged or sliding panels may be employed to provide exact control of the height and width of the openings 10.

Materials discharged from the bins by floor panels 6 fall upon a conveyor, shown as a conveyor belt 7, positioned beneath and in front of the leading edges of the floor panels 6. The belt carries the mixed discharged materials to an inclined chute 7a. This chute guides the materials into the upper open end of a rotary distributor chute 9 in the cupola, the chute 9 being formed with a side opening 9a for discharging the materials outwardly in a circular pattern or ring near the outer walls of the cupola. The rotary chute is carried by a supporting shaft 11 mounted on suitable bearings in a supporting bracket 11a in the upper portion of the cupola and is caused to rotate by means of gears 13 and motor-driven shaft 19 projecting through the cupola wall. The shaft 11 is positioned centrally of the cupola, the rotary chute 9 being positioned at a height such that its bottom edge is spaced a short distance above the normal upper surface of the burden in the cupola. The rotary distributing chute is of particular importance in the present invention since the usual burden contains many fines which should be carefully distributed and placed principally away from the center of the cupola, as provided by the outwardly directed spout 9a.

In order to regulate the relative quantity of each material discharged and to provide for adjustment from time to time of the relative quantities of each, the actuating mechanism illustrated in the drawings has been found to be particularly satisfactory. There is provided an actuating beam 14, pivoted at 15, near the center thereof, to an adjustable supporting bar 16. The supporting bar is adjustable in slots 17 on the base 18. The connection at the pivot 15 permits adjustment of the pivot with respect to the length of the beam, to correspond to the length-wise adjustment of the supporting bar. The beam is connected to the floor panels of the bins by means of links 20 pivotally connected to the beam on opposite sides of the hinge point 15 and to the floor panels. The beam is

caused to oscillate, to move the floor panels back and forth, by means of motor 21 and associated speed-reducing gear 22 mounted on bracket 23 which may be supported on the adjacent supply bin. The reducing gear box includes a slow moving power shaft at its lower end, formed with a crank arm 24, the crank pin of which is connected by a connecting rod or link 25 to the operating end of beam 14 by pivot 26.

The motor reduction gear is a standard form of variable drive having preferably three speeds regulated by a projecting control arm 28. It is generally sufficient to have three speeds, a normal speed when the control arm is in its central position, a higher speed for accelerating the supply when the lever is advanced and a lower speed when the lever is retarded. In FIGS. 2 and 3 the lever is shown in normal position. Movement ahead or to the right, as viewed in FIG. 4, produces low speed and to the left produces higher than normal speed. Stops 30 (FIG. 2) may be provided to prevent excessive movement of the arm 28 which might damage the control. The control arm is biased toward the higher speed position by tension spring 31.

It will be understood that more adjustment positions could be provided and that normal feed could be set, for example, somewhat higher than desired to maintain a constant level in the cupola, in which case a lower speed would be the only variation required. This applies equally where the feed is set lower than desired, adjustment for higher speed only being required.

The present invention provides for maintaining a substantially uniform depth of burden by providing a shoe, maintained in contact with the upper surface of the burden in the cupola for all normal operating conditions. Thus there is provided a contact shoe 32 rigidly connected to a mounting shaft 34, loosely mounted in guide brackets 35 secured to the wall of the cupola. The shaft 34 may have an adjustable ring 36 secured to its upper end to prevent the bar and shoe from dropping down below the control area.

For translating movements of the control shoe to the feed mechanism and for periodically elevating the shoe to prevent it from becoming buried in the charged materials, there is provided a rigid lever bar 38 pivotally connected to a supporting bracket 39 mounted on the furnace wall. The bar carries a yoke 42 at its inner end, the yoke extending beneath and engaging a ring 40, adjustably mounted on the shaft 34. The outer end 43 of bar 38 carries a right-angled pin 47, slidably mounted in slot 44 in a pitman or connecting rod 45, the lower end of which is attached to the actuating pin of crank 46 rotated by motor 48 and reduction gear 49. An exact adjustment of the height of the burden in the cupola can be made by a simple adjustment of the rings 36 and 40, lengthwise of the shoe supporting shaft 34.

The bar 38 is connected to the control arm 28 of the feed mechanism by means of cable 50 connected at one end to the bar 38, at a point outwardly beyond the pivot 37 and at its other end to the free end of control arm 28. The cable may pass over suitable pulleys, one such shown at 51, to provide a direct pull upon the arm 28, in opposition to the tension provided by spring 31.

The parts are so weighted and balanced that the shoe 32 normally rests upon or near the upper surface of the burden, the yoke 42 of bar 38 bearing against the ring 40 due to the extra weight of bar 38 outwardly beyond the pivot 37. As the burden in the cupola is consumed the shoe drops correspondingly, tilting the outer end of bar 38 upwardly and if this movement is sufficient the feed motor control is moved to high position, under the influence of spring 31. This condition is interrupted periodically, desirably once every minute or two, as the crank arm 46 moves downwardly, causing a brief engagement of the upper end of slot 44 with pin 47 on the outer free end of bar 38. The downward movement of the outer end of bar 38 elevates the shoe upwardly through

any overlying burden, causing temporary shifting of control arm to slow position. When the slot 44 releases the outer end of bar 38 shoe 32 drops again by gravity to the upper surface of the burden in the cupola, producing the setting for the feed mechanism corresponding to the new position of the shoe. Since the position of the shoe 32 corresponds generally with the radial position where the charge is deposited in the cupola, the burden presents a relatively flat surface to be contacted by the shoe, resulting in uniformity of operation.

The speed of movement of most elements of the apparatus is not critical and in general the movements are slow. Thus the speed of the conveyor belt is not critical, its speed being regulated to conveniently carry the discharged slag and coke mixture to the cupola. The charge-withdrawing operation is set to provide substantially the required amount of slag and coke to replace that removed in the melting operation of the furnace. The slow speed and high speed may be set at ten percent to twenty percent below and above, respectively, the normal operating speed. The rotary chute 9 may be rotated at a relatively slow rate, for example, one to two r.p.m., or even less, although a more rapid rate, up to twenty r.p.m. or more has been found not to be harmful. The motor and gear box for elevating the control shoe in the cupola may be set to provide one or two strokes per minute, that is, one or two r.p.m. of the crank arm 46.

It will be noted there is no synchronism between the various feeding, distributing and control devices herein, but that instead there is a random supply of slag and coke to the successive areas in the cupola. It has been found that the height of burden can be controlled within plus or minus about one inch, this being well within the limits required to accomplish the benefits of a continuous cupola feeding operation as herein described.

It has been found there are many benefits, some unanticipated, in maintaining a substantially constant height of burden in upright cupolas of the type herein described and in placing the charge in a ring near the outer wall or at least removed from the center of the cupola. Depositing the charge in a circular path results in a disproportionate amount of the smaller particles and fines remaining near the outer walls with the larger particles concentrated near the center of the cupola. This division between small and large particles is shown in exaggerated form in the drawings to illustrate the effect. There are actually small and large particles scattered across the burden, but with a greater concentration of fines nearer the walls and of coarser particles near the center of the cupola. The draft through the center of the cupola is thereby increased and the combustion area reaches well up into the center of the burden. The edge portions of the burden thus serve to insulate the side walls along a substantial portion of the combustion zone, resulting in less heat loss, the smaller particles being gradually melted or consumed as they collapse into the lower portion of the combustion zone where this zone spreads across the cupola.

The result is that there is a more uniform discharge of molten slag from the cupola, the discharged stream being of more uniform temperature and viscosity. This has proven to be of unexpected benefit in that the coke-slag-ratio can be reduced and there is better density control of the fiberized product and avoidance of the well recognized wide range in weight of fiberized product produced per unit of time, where the cupola is fed in the usual batch or intermittent manner. It is thus easier to meet manufacturing tolerances, with actual savings due in part to the insulating effect of the outer layer of fines surrounding a portion of the combustion zone.

It will be noted the charge is distributed outwardly from the spout 9a of the rotary chute 9. The path in which the charge is placed in the cupola accordingly

varies, dependent on the spacing of the chute 9 above the burden in the cupola, the greater the spacing the nearer the discharged materials fall with respect to the walls. The materials may also be discharged nearer the walls by increasing the speed of rotation of the chute. Either of these methods affords a ready adjustment of the placement of the charge in the cupola as required for the particular charge materials being used and the operating conditions of the cupola.

The operation of the apparatus will be clear from the above description. The initial charge is introduced and the charge ignited in any preferred manner. Thereafter the controls operate to maintain a substantially uniform depth of burden in the cupola due to the controls under the influence of the shoe 32. The materials are deposited in a ring near the outer walls so that the finer materials tend to accumulate near the walls and the coarser particles tend to fall toward the center. These particularly favorable operating conditions are continued indefinitely and without further attention except for maintaining a supply of slag and coke in the hoppers.

While the invention has been described in rather full detail, it will be understood that these details need not be strictly adhered to and that various changes and modifications may suggest themselves to one skilled in the art, all falling within the scope of the invention as defined by the subjoined claims.

What I claim is:

1. Apparatus for continuously introducing a charge of material to be melted and combustion agent into a cupola above the burden in said cupola comprising a plurality of bins containing either the material to be melted or the combustion agent, means responsive to a control device for removing varying amounts of said material to be melted and said combustion agent from said bins, means for commingling said removed material to be melted and said combustion agent, charging said cupola by introducing the commingled material to be melted and

5 combustion agent into said cupola, a distributor in said cupola for receiving said commingled material to be melted and said combustion agent, means mounting said distributor for rotation about an axis substantially parallel to the longitudinal axis of said cupola, means rotating said distributor to distribute said commingled material to be melted and said combustion agent in said cupola in a circular pattern spaced outwardly from the center of said cupola, said control device comprising a constant level contact member in said cupola, and means for periodically moving said contact member generally in a direction parallel to the longitudinal axis of said cupola from a position beneath the exposed surface of the burden of charged materials in said cupola to a position in contact with the free exposed surface of said burden.

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000
